THE COLUMBIA PLANOGRAPH CO., WASHINGTON, D. C.

UNITED STATES PATENT OFFICE.

GEORGE F. LONG, OF NEW YORK, N. Y.

MUFFLER CUT-OUT.

1,320,627.

Specification of Letters Patent.

Patented Nov. 4, 1919.

Application filed July 21, 1916. Serial No. 110,496.

To all whom it may concern:

Be it known that I, GEORGE F. LONG, a citizen of the United States, and resident of New York city, in the county of Queens and 5 State of New York, have invented certain new and useful Improvements in Muffler Cut-Outs, of which the following is a specification.

My invention relates to an improvement 10 in muffler cut-outs for installation within the length of the exhaust pipe from internal combustion engines and one of the primary objects of the invention is to provide a simplified commercial form of such devices designed so that it may be easily stamped 15 from sheet metal and constructed with a minimum amount of machining so as to be marketed at relatively low cost.

With some types of automobiles the exhaust pipe from the engine extends downwardly, is then bent horizontally at an angle to extend rearwardly of the car and terminates in a horizontal section of pipe leading to the muffler. The space taken up by 20 this horizontal section of pipe is admirably adapted to contain a muffler cut-out but in most makes of automobile this space is only about five or six inches in length. The usual size cut-outs necessary for an automobile engine cannot be fitted within this limited 25 space and if reduced in size would not provide the necessary size of expansion chamber nor the necessary clearance for the gases.

Accordingly, another object of my invention is to provide a muffler cut out which 30 will provide a clear, free escape for the gases from the engine and which, at the same time, may be proportioned and designed so as to be installed in a limited length of the exhaust pipe.

Incidental to the object of economical construction, further desiderata are to provide a device of the class described which can be stamped to shape from sheet metal of thin 45 gage material but assembled so as to reinforce interfitting parts, in which any necessary machining is either entirely avoided or reduced to a minimum and in which the parts may be assembled with the least possible amount of skilled labor.

Various other objects and advantages of the invention will be in part obvious from an inspection of the accompanying drawings and in part will be more fully set forth 50 in the following particular description of

one form of mechanism embodying my invention, and the invention also consists in certain new and novel features of construction and combination of parts hereinafter set forth and claimed.

60 In the drawings:

Figure 1 is a view in side elevation showing a preferred embodiment of my invention, and with parts broken away to show internal construction;

Figs. 2 and 3 are horizontal sectional views taken on the line 2-2 of Fig. 2 and showing the valve shell in its two operative positions.

The usual horizontal section of an exhaust 70 pipe 3 is cut away between the bend 4 and a muffler 5 to accommodate the cut-out 6. The body portion of the cut-out is formed of two cylindrical shells 7, 8, telescopically interfitting to have a gas-tight rotary fit. These 75 shells are stamped from sheet metal of relatively thin gage and one end of each shell is provided with a head 9 integral therewith and oppositely arranged so as to form a vertically disposed barrel containing an expansion chamber 10 with closed upper and lower ends.

The outer shell 7 constitutes a bearing for the inner valve shell and the wall of the outer shell is provided with a pair of diametrically disposed openings, one of which, 11, is designed to face the exhaust pipe 3 and the other of which, 12, is designed to face the muffler. These openings are relatively 85 large and preferably are rectangular with their longest dimensions vertical so as to utilize practically the entire length of the barrel. These openings have a cross-sectional area at least equal to that of the exhaust pipe and preferably should have a 90 larger area than the exhaust pipe thereby to insure a sufficient clearance for the gases.

A pair of fittings 13 constitute extensions from opposite sides of the body portions and coact therewith normally to form a continuation of the exhaust pipe line to the muffler. The fittings are attached to the exhaust pipe and to the muffler inlet pipe 14 by set screws 15 as is usual with devices of this character, or, if desired the interengaging 100 parts may be screw-threaded as shown at 16 in Figs. 2 and 3. The portion of the fittings adjacent the body portion are reduced transversely of the length of the shells as shown in Figs. 2 and 3 and are elongated length- 105 110

wise of the same as shown in Fig. 1 to form frusto-pyramidal end walls 17, forming rectangular throats 18 outlining the openings 11 and 12. The ends of the walls 17 are flared outwardly to form attaching flanges 19 fitting the side of the outer shell about the openings. The flanges are secured to the outer shell preferably by rivets 20 the inner ends of which are countersunk so as not to interfere with the fit of the telescoped shells. The outer shell is also provided with an outlet port 21 similar in design to and positioned between the openings 11 and 12.

The inner valve shell 8 is provided with a pair of circumferentially spaced openings 22 and 23 designed to form continuation respectively of the openings 11 and 12 when the shells are in their normal position with the exhaust pipe open direct to the muffler as shown in Fig. 2. The opening 22 corresponds in dimensions with the opening 12 to the muffler but the opening 23 is of such a length that it may be disposed across both the opening 11 and across the port 21 when the valve shell is in the position shown in Fig. 3. The openings are so spaced relative to each other that the shells in one position will open the muffler to the expansion chamber and close the exhaust port and in another position will open the exhaust port to the outside air and close off the muffler.

The shells are demountably fastened together by a pivot shaft 24 which is passed through the center of one of the heads 9 and has its opposite end squared and fastened to the other head. The shaft is provided with an actuating lever arm 25 by means of which the valve shell may be rotated. The end of the shaft opposite the end to which the lever arm is fixed projects beyond the adjacent shell head and is provided with lock nuts 26 designed to hold one end of a spring 27 coiled about the projecting portion of the shaft. The end of the spring adjacent the head is fastened to a stud 28 projecting from the head slightly off-centered therefrom. The springs act on the shaft to rotate the valve shell into normal set position providing a free open passageway to the muffler.

In operation, the gases normally pass from the exhaust pipe through the expansion chamber and into the muffler as is usual with devices of this character. A transverse pull on the connection attached to the lever arm causes the valve shell to rotate in the direction indicated by the arrow in Fig. 2 into the position shown in Fig. 3, thus closing communication with the muffler and opening the expansion chamber direct to the outer air. Releasing the pull on the lever arm permits the spring to re-rotate the valve shell and restore the parts to their normal position.

In a device of this character, it is possible

to form the parts conveniently and cheaply from thin sheet-metal stampings which will take up less room than the heavy metal castings of which such devices are usually constructed. Further, the device can be made of a capacity sufficient for use in automobile engines and at the same time may have a diameter to fit within the limited 5 or 6 inch space provided in the exhaust pipe length of some automobile constructions. A device designed as described will give sufficient clearance horizontally for the gases as they pass through the device, especially with the large size of openings provided, and as the device may be made of any convenient length vertically any desired size of expansion chamber may be provided at relatively small additional cost over small size devices now on the market. As the shells are cylindrical and interfitting, they mutually reinforce each other, thus permitting the use of a minimum amount of material.

In some forms of muffler cuts it has been usual to provide a holding spring for the movable valve element of sufficient strength to prevent flapping of the movable parts when subjected to the variable pressures from the exhaust pipe. While a string may be used in the device illustrated for the purpose of restoring the parts to their normal position, this spring has a tension merely sufficient to overcome the frictional resistance between the shells and need not be the heavy expensive springs usually found in devices of this character. All fluttering of valve elements, with the resulting wear and annoyance caused by the noise of loosening of parts is eliminated in the device disclosed. As the shells can be drawn to an accurately interfitting size and as all other parts may be stamped to shape and assembled practically without any machining, the cost of construction is reduced to a minimum. The parts may be readily separated simply by loosening the binding nuts at one end of the shaft and the telescoped parts withdrawn from each other.

While I have shown and described, and have pointed out in the annexed claim, certain novel features of the invention, it will be understood that various omissions, substitutions and changes in the form and details of the device illustrated and in its operation may be made by those skilled in the art without departing from the spirit of the invention.

Having thus described my invention, I claim:

A muffler cut out comprising two cylindrical sheet metal shells telescopically interfitting to have a gas tight rotary fit, heads defining opposite ends of said shells to form an upstanding closed expansion chamber, opposite sides of the outer shell provided

with elongated openings extending lengthwise of the shells thereby to obtain the maximum possible area of opening, fittings opening into said elongated openings and adapted to connect the cut-out to the muffler and exhaust pipe, the inner shell provided with openings adapted to register with the open-

ings in the outer shell and a control projecting from the top of the inner shell for actuating the same.

Signed at New York city, State of New York, this fifteenth day of June, A. D. 1916.

GEORGE F. LONG.
